UNITED STATES PATENT OFFICE.

FRANK L. PUTNAM, OF HOUSTON, TEXAS.

WATER HEATER.

Application filed June 19, 1923. Serial No. 646,296.

To all whom it may concern:

Be it known that I, FRANK L. PUTNAM, a citizen of the United States, residing at Houston, in the county of Harris and State 5 of Texas, have invented certain new and useful Improvements in a Water Heater, of which the following is a specification.

This invention relates to new and useful improvements in a water heater.

10 One object of the invention is to provide a water heater of the character described having an improved type of water coil, consisting of an outer coil through which the water passes upwardly from the inlet, 15 and an inner coil through which the water returns to the outlet, the coil thus passing twice through the burner flame thus subjecting the water in the coil to the heat twice before its discharge. At its upper end the 20 coil is enlarged or flared which tends to retain the heat in the burner casing and prevents it from passing too readily from the casing. The outer coil is spaced some distance out from the inner coil.

25 Another object of the invention is to provide at the top of the housing a coil support and a baffle plate between which the upper turns of the coil are clamped to support the coil and prevent its vibration.

30 A further object is to provide a water heater having a substantially conical shaped baffle, forming also a support for the coil intermediate its top and bottom, as well as a condensation plate.

35 A further feature resides in the provision of a water heater having an upper drip pan arranged substantially on a horizontal plane with respect to the burner opening, and of somewhat smaller diameter than the coil, 40 and a lower drip pan arranged under the bottom, or shelf, of the housing.

A still further feature of the invention resides in the provision of a central clamp rod whereby the upper baffle plate and the 45 upper drip pan may be clamped in position.

This invention also embodies a new form of supporting bracket specially adapted for supporting the heater on a wall.

With the above and other objects in view

50 the invention has particular relation to certain novel features of construction, arrangement of parts and use an example of which is given in this specification and illustrated in the accompanying drawings, wherein:—

55 Figure 1 shows a vertical sectional view of the heater.

Figure 2 shows a transverse sectional view, taken on the line 2—2 of Fig. 1.

Figure 3 shows a plan view of the top baffle plate.

Figure 4 shows a plan view of the coil support.

Figure 5 shows a plan view of the baffle and condensation plate forming also a coil support.

Figure 6 shows a plan view of a supporting bracket employed, and,

Figure 7 shows a side view thereof.

In the drawings the numeral 1 designates the housing, preferably of hexagonal contour. The bottom of the housing is formed of an annular shelf 2 having a central opening 3, underneath which there is a bottom drip pan 4. Said shelf declines toward its central opening so that the drippings falling 75 onto the shelf will run into said drip pan 4.

The top 5 of the housing is preferably conical in form and provided with a central opening 6 over which there is an annular hood 7. Formed in the under side of the 80 shelf 2 there is an annular gas passageway 8 into which the gas supply pipe 9 is connected, and from which the burners 10 are supplied with gas.

The numeral 11 designates a yoke which 85 is solid and whose respective ends have the inlet and outlet tubular connections 12 and 13. There is a double water coil, formed of the outer coil 14, and the inner coil 15 preferably of copper. The former is connected to the connection 12 and is coiled upwardly and is enlarged at its upper end, as shown in Figure 1 and is then continued, forming the inner coil which is connected to the outlet connection 13. There is a 90 ringlike support 16 in the upper end of the housing having the inwardly extending supporting fingers 17 on which the enlarged upper coils lie, and a baffle plate 18 is located above the coil, having the radiating 95 supporting lugs 19 which rest on the coil. A clamp rod 20 has its lower end threaded through the yoke and its upper end is fitted through a central opening of the baffle plate 18, and is threaded to receive the 100 nut 21.

There is an annular conical shaped condensation plate 22, anchored in the housing, intermediate the ends thereof, which surrounds the coil and has the arcuate brackets 110 22' which rest against said coil to support it. This plate also deflects the heat inwardly

toward the coil, and its upper surface catches the drippings falling from the enlarged upper turns of the coil and vaporizes the same. This plate has a marginal upturned rib 23 which catches and holds the surplus water until the same is vaporized by the heat of the plate.

The lower end of the anchor rod extends beneath the yoke 11 and the upper drip pan 24 is secured thereto. This drip pan is somewhat smaller in diameter than the diameter of the coil and it is provided to catch the water which condenses on, and drips from, the coil. In case it overflows, the overflow will fall onto the shelf 2 and then into the lower drip pan 4. The pan 2 is located near the horizontal plane of the burner opening and is consequently kept hot and will ordinarily vaporize all, or most of, the water dripping into it.

The water enters the outer coil 14, from the inlet pipe 25, and passes up through said outer coil 14, and back through the inner coil 15, and out through the outlet pipe 26, thus being subjected twice to the heat of the burner flames.

The flames are emitted from the burners at a slight inclination above a horizontal plane toward the coils and the heat is retained somewhat around the inner coil 15, by the outer coil 14. The heat is also deflected inwardly by the plate 22 toward the coils and is retained in the housing by the enlarged turns of the coil, and the baffle plate 18, at the top, thus obtaining the greatest heat efficiency.

For supporting the heater I have provided a novel type of support shown in detail in Figures 1, 6, and 7. In these figures the numeral 27 designates a wall plate, whose upper edge has the spaced dovetailed notches 28, 28. The numerals 29, 29, designate brackets of a general triangular shape, which have dovetailed catches 30, which engage in said notches. The vertical arm of each bracket rests against the wall, and the horizontal arm is provided on its upper side with the supporting flat top heads 31, 31.

The bottom of the housing has the two

depending legs, 32, 32, angular in cross section, as shown in Figure 2, which fit over the outer heads 31, and the bottom of the housing rests on said four heads which form a substantial support therefor.

What I claim is:

1. A water heater including a housing, a ring of burners located in the lower part thereof, a water coil within the housing whose lower end is approximately in the horizontal plane of the burner nozzles, a drip pan located within the ring of burners beneath said coil, a fixed yoke to which said coils are attached, a clamp rod attached to said yoke at lower end of which said drip pan is attached, a baffle plate on top of the coil to which the upper end of said rod is connected.

2. A water heater including a housing, a ring of burners in the housing, a water conducting coil in the housing above the burners, a baffle plate on said coil, a drip pan within the ring of burners beneath the coil, an anchor rod secured at its upper end to said plate and to the lower end of which the drip pan is attached, a yoke connecting said coils to which said rod is anchored.

3. A water heater including a housing, a single water conducting coil in the housing, formed of two series of turns, one series being located within the other, a top baffle plate located on the coil, said coil being widened at the top by the formation of additional turns, supporting means carried by the housing and extending underneath said widened portion, a fixed yoke into which the lower ends of the coil are connected, a clamp rod connected at its upper end to said baffle plate, a drip pan attached to the lower end of said rod beneath said coil, said rod being anchored to said yoke.

In testimony whereof I have signed my name to this specification in the presence of two subscribing witnesses.

FRANK L. PUTNAM.
